UNITED STATES PATENT OFFICE.

CHARLES V. CHAMPION, OF CATLIN, ILLINOIS.

DESIGN FOR AN ELECTRIC TOASTING DEVICE.

Application filed April 23, 1928. Serial No. 26,422. Term of patent 14 years.

To all whom it may concern:

Be it known that I, CHARLES V. CHAMPION, a citizen of the United States, residing at Catlin, in the county of Vermilion and State of Illinois, have invented a new, original, and ornamental Design for an Electric Toasting Device, of which the following is a specification, reference being had to the accompanying drawing, forming a part thereof.

Figure 1 is a side elevation,
Figure 2 is a front elevation, and
Figure 3 is a plan view.

I claim:

The ornamental design for an electric toasting device, substantially as shown.

CHARLES V. CHAMPION.
